United States Patent Office

Des. 184,580
Patented Mar. 10, 1959

184,580

TOW TRACTOR

Marlan H. Polhemus, Chicago, Ill.

Application April 28, 1958, Serial No. 50,648

Term of patent 14 years

(Cl. D14—3)

FIG. 1

FIG. 2

Des. 184,580

PAGE 2

FIG. 3

FIG. 4

FIG. 5

Figure 1 is a top front perspective view of a tow tractor, embodying my new design;

The essential features of my design reside in those portions shown in full lines.

I claim:

The ornamental design for a tow tractor, as shown and described.
